Nº 3480

PATENTED
MAY 11 1869

5.

In possession of
John Leavitt
George Margatroyd
Hugh Christie

United States Patent Office.

HUGH CHRISTIE OF MORRISANIA, ASSIGNOR TO DEBORAH POWERS, ALBERT E. POWERS, AND NATHANIEL B. POWERS, OF LANSINGBURG, NEW YORK.

Design No. 3,480, dated May 11, 1869.

DESIGN FOR A FLOOR OIL-CLOTH.

The Schedule referred to in these Letters Patent and making part of the same.

To all whom it may concern:

Be it known that I, HUGH CHRISTIE, of Morrisania, in the county of Westchester, and State of New York, have invented or produced a new and original Design for Floor Oil-Cloths, or other fabrics; and I do hereby declare that the same is fully shown upon the accompanying drawings, which I hereby declare to be part of this specification; and

What is claimed as my invention, and desired to be secured by Letters Patent of the United States, is—
The design for floor oil-cloths, or other fabrics, as shown upon the aforesaid drawings.

HUGH CHRISTIE.
